UNITED STATES PATENT OFFICE.

NELS A. ANDER, OF BATAVIA, ILLINOIS.

DESIGN FOR A SLEIGH-BELL.

SPECIFICATION forming part of Design No. 28,197, dated January 18, 1898.

Application filed December 18, 1897. Serial No. 662,490. Term of patent 14 years.

To all whom it may concern:

Be it known that I, NELS A. ANDER, a citizen of the United States, residing at Batavia, in the county of Kane and State of Illinois, 5 have invented and produced a new and original Design for a Sleigh-Bell; and I do hereby declare the following to be a full, clear, and exact description thereof, reference being had to the accompanying drawings, forming a part 10 thereof.

Figure 1 is an elevation, and Fig. 2 a bottom plan.

The principal feature of my design is comprised in the series of slots A, formed in the 15 spherical body of the bell B. These slots

start from a common center *a* in the bottom of the bell, and, radiating therefrom, stop short of the top and give the bell the appearance of being formed of a number of segments.

A second feature of the design is the horizontal encircling band or belt C.

The aperture D merely indicates the core-hole necessary in casting the hollow sphere.

What I claim is—

The design for a sleigh-bell, substantially 25 as herein shown and described.

NELS A. ANDER.
